CARBURETOR

Lester H. Messinger, Jr., Trumbull, Conn., assignor to Messinger Devices, Incorporated, Bridgeport, Conn., a corporation of Connecticut

Application February 18, 1933, Serial No. 657,337

16 Claims. (Cl. 261—34)

This invention relates to new and useful improvements in priming or accelerating means for internal combustion engines.

At the present time at least one internal combustion engine carburetor is constructed with a small pump in its float chamber and which pump due to a vacuum created while the engine (with which the carburetor is associated) is idling is drawn to a position where the pump is loaded or charged with gasoline and when the accelerator or throttle of the carburetor is suddenly advanced or opened the vacuum is broken and spring means functions to operate the pump to have it spray gasoline into the charge forming passage of the carburetor. These pumps are not reliable in their operation and often times do not function at all. Also, when an engine is equipped with a carburetor by-pass valve means as disclosed in my applications Serial No. 102,347 filed April 15th, 1926, which matured to Patent #1,910,350, granted May 23, 1933, and Serial No. 653,255, filed January 24th, 1933, the vacuum normally used for operating the pump is not present or available and the pump functions at the wrong time.

An object of the present invention is to provide a means whereby the accelerating discharge pumps above referred to are reliably operated under all circumstances.

Another object is to provide a means for operating an accelerating discharge pump of a carburetor and which means is automatically controlled or operated by the throttle operating means of the carburetor.

A further object is to provide a means for the purpose stated and which is simple in construction and easily installed for use.

Other objects and advantages will become apparent from a consideration of the following detailed description taken in connection with the accompanying drawing wherein a satisfactory embodiment of the invention is shown. However, it will be understood that the invention is not limited to the details disclosed but includes all such variations and modifications as fall within the spirit of the invention and the scope of the appended claims.

In the drawing:

Fig. 1 is a side elevational view showing a carburetor equipped with the means of the present invention;

Fig. 2 is an end elevational view thereof looking from the right in Fig. 1;

Fig. 3 is a view partly in plan and partly in

section, the view being taken substantially along the line 3—3 of Fig. 1;

Fig. 4 is a vertical sectional view taken substantially along the line 4—4 of Fig. 3;

Fig. 5 is a vertical sectional view taken substantially along the line 5—5 of Fig. 3; and

Fig. 6 is a view somewhat similar to Fig. 5 but showing the pump at the end of its discharge stroke.

Referring in detail to the drawing, at 10 is generally indicated a carburetor including a bowl 11 to which gasoline is supplied from any suitable source through a tube or pipe line 12. Also, within the carburetor is an intake passage 13 controlled by any or the usual throttle valve 14 mounted on a shaft 15 and above the throttle valve is any or the usual jet 16 for spraying gasoline into the venturi 17 of the intake passage 13.

The present invention has no particular relation to the operation of the jet 16 of the carburetor. Chamber 18 within the bowl 11 may be equipped with any or the usual float controlled valve means (not shown) for regulating the height of gasoline in the chamber. Within the chamber 18 there is arranged a pump 19 forming a usual part of the carburetor and separated from the pump as by a wall or other means 20 is a vacuum and spring controlled means 21 for operating the pump. By means of tubing or the like (not shown) connected at 22, the means 21 is placed in communication with the suction or intake side of an internal combustion engine of any or the usual construction (not shown). The means 21 includes an outer cylinder 23 and a piston 24 and within the cylinder 23 and piston 24 and normally tending to force the piston upwardly is a coil spring 25. A small orifice places the cylinder in communication with the connection 22.

Pump 19 by means of a link 26 is connected with one end of a rocker 27 pivotally mounted as at 28 and the other end of this rocker is connected with the piston 24 of the vacuum means 21 as by a link 29.

An economizer valve is arranged in the chamber 18 and includes a poppet valve 53 normally maintained on its seat by means of a coil spring 54 disposed about its stem 55. The spring 54 bears against a collar 56 on the stem and a housing 57 through which the stem passes and which housing is within the chamber 18. Housing 57 has an opening 58 in the float chamber and when valve 53 is unseated gasoline passes through said opening and downwardly about the valve stem and through a port 59.

to a channel 60 leading to the high speed jet 16. At its upper end valve stem 55 carries a head 61 to be engaged at the proper times by the rocker 27 which acts to unseat the valve.

5 In the operation of the device when the engine is operating in a manner to create a high vacuum, as when the engine is idling or when it is operating at high speed with the throttle advanced, the suction applied to the means 21 through the connection 22 serves to cause the piston 24 to move downwardly in the cylinder 23 against the action of the spring 25 and, of course, the spring is compressed. As the piston of the means 21 moves downwardly it acts through link 29 to shift the rocker 27 from the position of Fig. 6 to that of Fig. 5 whereby the pump 19 is drawn upwardly in the chamber 18 and gasoline enters the pump and the pump becomes loaded or charged. This upward movement of the rocker 27 also permits the spring 54 to seat the valve 53.

Assuming the parts to be in the relative positions in which they are shown in Fig. 5 should the throttle valve 14 be suddenly opened the vacuum created by the engine will be materially reduced and the spring 25 will act to shift the piston 24 of means 21 upwardly whereby the parts will move into the positions in which they are shown in Fig. 6. In this movement pump 19 has been operated to discharge gasoline and the gasoline is discharged into a passage 30 which in turn is in communication with a passage 31 at its upper end communicating with a nozzle or jet 32. This nozzle 32 constitutes the accelerating or pump discharge jet of the carburetor and the gasoline discharged by the pump 19 is sprayed through the jet 32 into the venturi of the carburetor. This pumping means is a priming device or boosting device and is designed to spray gasoline into the venturi 17 when the throttle valve 14 is suddenly opened from idling or closed position. Also, when the engine is operating with a constant throttle the suction on means 21 raises the pump to loading position and when a grade is encountered the engine slows up and the vacuum is reduced and spring 25 will act to discharge the pump. When the car passes the crest of the hill the engine again speeds up and the pump is drawn up to charged or loaded position.

The mechanism as thus far described is all incorporated in a carburetor at present on the market. As above suggested the suction means for operating the pump 19 to loading position or condition is not reliable since the means sometimes becomes clogged and does not function. Further, when it does function it does not operate to always discharge the same quantity of gasoline and when an automobile is being parked after the engine is stopped and the vacuum or suction on the means 21 fails the pump operates to spray gasoline through the jet 32 and such gasoline is wasted. Also, when a by-pass valve means such as disclosed in my above entitled applications is employed there is no vacuum available to operate the means 21. With the parts positioned as in Fig. 6 the economizer valve is open and an extra steady stream of gasoline is being fed. However, when the device functions properly the parts are normally positioned as in Fig. 5 with the economizer valve closed and this valve is opened at the end of the discharge stroke of the pump 19.

The means for operating the throttle valve 14 includes an arm 33 secured to the outer end por-

tion of the valve stem or shaft 15 and adapted to be shifted to rock said stem whereby the valve will be opened and closed. To this arm is attached a bar or rod 34 which may extend rearwardly and be attached to or provide a means to be manipulated by the hand or foot of an operator to open the valve 14.

To open the throttle valve the arm 33 is rocked in the direction indicated by the arrow 35 in Fig. 2 and during such motion an extensor 36 of the arm is rocked downwardly tensioning a coil spring 37. As soon as the pressure on the arm 33 is relieved the spring 37 will act to return the parts to their normal position or to their position in which the valve 14 is closed. A set screw 38 is provided to control the movement of the parts under the action of the spring 37. This is all more or less standard construction and it will be noted that the upper end of the spring 37 is anchored to a clip 39 secured to the carburetor as by being clamped on to a bolt 40 provided for that purpose.

According to the present invention, a bracket or casting 41 is secured to the upper side of the carburetor 10 and the bracket is substantially L-shaped and the end portion of its arm 42 is disposed over the bolt 40 while the end portion of its arm 43 is secured or anchored as by screw 44. On its upper surface the arm 43 carries a pair of spaced bearings 45 in which a rod 46 is mounted for oscillation and this rod has a bent end portion 47 constituting a rocker arm. The free end of rocker arm 47 is bent laterally as at 48 in Fig. 3 to extend under the rocker 27 at one side of the pivot 28 thereof.

An arm 49 is clamped to the other end of the rod 46 and extends in the same general direction as the rocker arm portion 47. However, as the description proceeds it will become evident that this is a matter of convenience and that the arms 47 and 49 do not necessarily extend in the same general direction. A push rod 50 has its lower end portion connected to or mounted on a pin 51 carried by the extension or portion 36 of arm 33 and this is the same pin to which the lower end 45 of spring 37 is connected. The upper end portion of push rod 50 passes through a guide portion 52 of the arm 41 of bracket 40 and is adapted to engage the arm 49. That is, the rod 50 may be projected to engage and raise the arm 49 and 50 may be retracted to permit said arm to descend.

Figs. 2 and 5 clearly show the positions of the parts when the throttle operating mechanism is retarded or when the throttle valve is closed. It will be noted that in such position the push rod 50 is projected and the arm 49 is elevated the lower position of said arm being shown in broken lines in Fig. 2. Further, by particular reference to Fig. 5 it will be noted that when the rocker arm 47 is elevated the pump 19 is in loaded or 60 charging position.

When the throttle operating mechanism is retarded, either when the engine is idling or when the ignition is cut off, the parts will be positioned as best shown in Figs. 2 and 5 and the pump 19 will be loaded or charged. As soon as the throttle mechanism is advanced as when starting an engine or increasing its speed over idling speed the push rod 50 is drawn downwardly with the result that there is no force to sustain the rocker arm 47 against the rocker 27 to hold the pump in charging position against the action of spring 25 and said spring therefor acts to shift rocker 27 about its pivot 28 from the position of Fig. 5 to that of Fig. 6 and the pump 19 discharges forc-

ing gas through the passage 30 to the passage 31 and causing the jet 32 to spray the gasoline into the charge forming passage or venturi of the carburetor.

5 From the foregoing description it will be understood that as the throttle operating mechanism is shifted to retarded position by the coil spring 37 the push rod 50 will act through arm 49, rod 48 and rocker arm 47 to shift the rocker 27 about its pivot and raise the pump 19 to loaded or charging position. The pump is positively shifted or raised to such position and there is no dependence on vacuum to accomplish this function. Therefore, whenever the throttle is retarded the 10 pump will be loaded or charged and will discharge to spray gasoline through the jet 32 whenever the throttle is again advanced if the vacuum drops sufficiently.

This discharging of the pump is, of course, effected by the coil spring 25 on the push rod 50 being retracted to permit of lowering of the rocker arm 47. Attention is also directed to the fact that when the engine is stopped as when an automobile is being parked the pump will be held 15 in loaded or charged position and will not discharge due to the failure of a vacuum after the ignition circuit is opened. It will also be noted that the means of the present invention is here disclosed as in the nature of an attachment and 20 that the same does not require any change in the construction of the carburetor and does not in any way interfere with the normal operation of the carburetor.

It will also be apparent that the present means 25 does not in any way detract from the usefulness of the economizer valve. This valve will be opened in the usual manner and at the usual times. With the present attachment to place on a carburetor the pump will be returned to charged 30 or loaded position immediately on the throttle means being retarded and the economizer valve is also permitted to immediately return to its seat. When the throttle is retarded it is not necessary 35 to wait for the vacuum to raise the pump and release the valve 53 since this will be done mechanically and further, if the pump is loaded and the engine stopped the arm 47 will retain the 40 pump in its loaded position.

Having thus described the nature of the invention, what is claimed is:

1. In combination, a carburetor including a throttle valve and a gasoline chamber, means to advance said throttle valve toward open position and other means to return it toward retarded position, a pump communicating with the gasoline chamber of the carburetor, a rocker connected at one end with said pump, a spring means connected with the other end of said rocker and normally tending to operate the pump to have it discharge, said pump adapted when discharging to spray gasoline into the intake passage of the carburetor, a rocker arm engaging said rocker, and means whereby as the throttle operating mechanism of the carburetor is retarded said rocker arm operates said rocker to operate said pump toward loading position and as said throttle operating means is advanced said rocker arm moves out of the way to permit said spring means to function.

2. In combination, a carburetor including a throttle valve and a gasoline chamber, means to advance said throttle valve toward open position and other means to return it toward retarded position, a pump communicating with the gasoline chamber of the carburetor, a rocker connected

at one end with said pump, a spring means connected with the other end of said rocker and normally tending to operate the pump to have it discharge, said pump adapted when discharging to spray gasoline into the intake passage of the carburetor, a rod rotatably mounted on said carburetor, an arm on said rod and projecting to engage said rocker, a second arm on said rod, a push rod adapted to be projected to engage said second arm and rock the rod to have its first arm 10 engage the rocker to operate the pump to loading position and to be retracted away from the said second arm of the rod to release the rocker in order that the pump may be operated by the spring means, and means to project and retract 15 said push rod as the throttle valve is advanced and retarded.

3. In combination, a carburetor including a throttle valve and a gasoline chamber, means to advance said throttle valve toward open position and other means to return it toward retarded position, a pump communicating with the gasoline chamber of the carburetor, vacuum operated means to operate said pump toward loaded position, means to operate said pump to 25 spray gasoline into the intake passage of the carburetor on opening of the throttle valve, and means controlled by the throttle valve operating means to reset the pump for operation by the pump operating means.

4. In combination, a carburetor including a throttle valve and a gasoline chamber, means to advance said throttle valve toward open position and other means to return it toward retarded position, a pump communicating with the gasoline chamber of the carburetor, vacuum operated means to operate said pump toward loaded position, means to operate said pump to spray gasoline into the intake passage of the carburetor on advancing of the throttle valve, and positively 40 operated means controlled by the throttle valve operating means to reset the pump for operation by the pump operating means.

5. In combination, a carburetor including a throttle valve and a gasoline chamber, means to advance said throttle valve toward open position and other means to return it toward retarded position, a pump communicating with the gasoline chamber of the carburetor, vacuum operated means to operate said pump toward loaded position, spring means to operate said pump to spray gasoline into the intake passage of the carburetor on opening of the throttle valve, and means controlled by the throttle valve operating means to reset the pump for operation by the spring means.

6. In combination, a carburetor including a throttle valve and a gasoline chamber, means to advance said throttle valve toward open position and other means to return it toward retarded position, a pump communicating with the gasoline chamber of the carburetor, vacuum operated means to operate said pump toward loaded position, spring means to operate said pump to spray gasoline into the intake passage of the carburetor on advancing of the throttle valve, and positively 60 operated means controlled by the throttle valve operating means to reset the pump for operation by the spring means.

7. In combination, a carburetor including a throttle valve and a gasoline chamber, means to advance said throttle valve toward open position and other means to return it toward retarded position, a pump communicating with the gasoline chamber of the carburetor, vacuum operated means to operate the pump toward loaded 75

position, spring means to operate said pump to spray gasoline into the intake passage of the carburetor on advancing of the throttle valve, and means controlled by the throttle valve operating means and operated thereby on its movement toward throttle valve closing position to reset the pump for operation by the spring means.

8. In combination, a carburetor including a throttle valve and a gasoline chamber, means to advance said throttle valve toward open position and other means to return it toward retarded position, a pump communicating with the gasoline chamber of the carburetor, vacuum operated means to operate said pump toward loaded position, means to operate said pump to spray gasoline into the intake passage of the carburetor on advancing of the throttle valve, and positively operated means controlled by the throttle valve operating means to move the pump to fully loaded position as the throttle valve operating means moves to retarded position.

9. In combination, a carburetor including a throttle valve and a gasoline chamber, means to advance said throttle valve toward open position and other means to return it toward retarded position, a pump communicating with the gasoline chamber of the carburetor, vacuum operated means to operate the pump toward loaded position, means to operate the pump to spray gasoline into the intake passage of the carburetor on advancing of the throttle valve and means controlled by the throttle valve operating means and operated thereby on its movement toward throttle valve closing position to reset the pump in loaded position.

10. In combination, a carburetor including a throttle valve and a gasoline chamber, means to advance said throttle valve toward open position and other means to return it toward retarded position, a pump communicating with the gasoline chamber of the carburetor, a rocker connected at one end with said pump, means connected with the other end of said rocker and normally tending to operate the pump to have it discharge, said pump adapted when discharging to spray gasoline into the intake passage of the carburetor, a rocker arm engaging said rocker, and means whereby as the throttle operating mechanism of the carburetor is retarded said rocker arm operates said rocker to operate said pump toward loading position and as said throt-

tle operating means is advanced toward open position of the throttle said rocker arm moves out of the way to permit said pump operating means to function.

11. In a carburetor including a throttle and a throttle lever, a fuel pump adapted to be operated to charged position by vacuum, and throttle lever operated means operable to cause charging of said pump as the throttle lever is moved to throttle closing position.

12. In a carburetor including a throttle and a throttle lever, a fuel pump adapted to be operated to charged position by vacuum, and throttle lever operated means positively operable to cause charging of said pump as the throttle lever is moved to throttle closing position.

13. In a carburetor including a throttle and a throttle lever, a fuel pump adapted to be operated to charged position by vacuum, and throttle lever operated means operable to cause charging of said pump as the throttle lever is moved to throttle closing position and to hold the pump in charged position while the throttle lever is in throttle closing position.

14. In a carburetor including a throttle and a throttle lever, a fuel pump adapted to be operated to charged position by vacuum, and throttle lever operated means operable to cause charging of said pump as the throttle lever is moved to throttle closing position and positively operable to hold the pump in charged position while the throttle lever is in throttle closing position.

15. In a carburetor including a throttle and a throttle lever, a fuel pump adapted to be operated to charged position by vacuum and throttle lever operated means for rendering the fuel pump inoperative, said means being so constructed and arranged as to permit of movement of the throttle to closed position irrespective of the position of the pump at the beginning of such movement.

16. In a carburetor including a throttle and a throttle lever, a fuel pump adapted to be operated to charged position by vacuum, and throttle lever operated means for rendering the fuel pump inoperative, said means being so constructed and arranged as to insure that the pump is in a loaded position when said means becomes effective to render the pump inoperative.

LESTER H. MESSINGER, JR.
